F. G. Fischer,
ATTORNEY.

UNITED STATES PATENT OFFICE

2,515,924

NONMELTING CANDLE

Paul A. Hunicke, Kansas City, Mo.

Application September 29, 1947, Serial No. 776,802

1 Claim. (Cl. 67—55)

1

The present invention relates more particularly to a permanent or nonmelting candle embodying a fuel chamber, a burner, and a wick.

One object is to provide a permanent candle which can be maintained at less expense than the customary wax or composite candle, much of which is consumed by the flame while most of the remainder becomes melted by radiant heat from the flame and runs down upon the outer surface of the candle and the candle holder, thereby producing an unsightly appearance.

Another object of the invention is the provision of a plural strand wick, the main strand of which extends upward from the fuel chamber and through the burner where it may be ignited, the other or feeder strands extending from the lower to the upper portion of the fuel chamber where they are formed into a loop through which the main strand may be drawn outward from time to time as it is consumed by the flame, and on becoming too short to reach down into the liquid fuel, is supplied therewith by the feeder strands which constantly remain the same length.

Other objects will hereinafter appear, and in order that the invention may be fully understood, reference will now be had to the accompanying drawing, in which:

Fig. 1 is a longitudinal sectional view of the candle with a burner mounted upon the upper end thereof.

Fig. 2 is a longitudinal section of a fuel tank adapted to be fixed within a composite candle as the candle is being molded.

Fig. 3 is a plan view of a modified form of burner.

Fig. 4 is a perspective view of the modified form of burner associated with a wick.

Fig. 5 is a vertical sectional view of another modified form of burner.

In carrying out the invention I employ a candle 2 which may be cast from composite material, metal, or be fabricated from sheet metal. As shown by Fig. 1 the candle tapers towards its upper end 4 the greater portion of its length, while its lower portion tapers towards its lower end 6, to snugly fit into a candle holder, not shown. The candle may be made in many different sizes for use in churches, the household, or wherever candles are needed. When molded from composite material the candle is reinforced by a liquid fuel tank 8 comprising a cylindrical body portion 10 closed at its bottom portion 12, and open at its upper end, which latter preferably reaches to the upper open end of the candle.

The tank 8 may be of any desired length and

2

provided at its closed bottom portion 12 with a wire 14 which extends downwardly to the lower end of the candle as shown by Fig. 1. When the candle 2 is cast from metal or fabricated from sheet metal or other suitable material, the fuel tank 8 and the reinforcing wire 14 may be dispensed with, in which instance a fuel chamber will be formed directly in the body of the candle.

The upper open ends of the candle 2 and the fuel tank 8 are normally closed by a burner 16 made from metal or other nonmelting material and provided with a flanged base 18 whereby it is held upon the upper end of the candle. The burner may be made in various forms, such for example as that shown at the upper end of Fig. 1, and those disclosed by Figs. 3, 4 and 5. As shown by Fig. 1 the burner 16 has an upwardly tapered tip 20 and an axial bore 22, which latter extends vertically through the burner. The modified form of burner disclosed by Figs. 3 and 4, has a semispherical top 24 with a peripheral flange 26 at its lower portion to fit over the upper end of the candle 2 and the fuel tank 8. The modified form of burner 28 shown by Fig. 5, is somewhat elongated and tapers towards its upper and lower ends, and like the other burners has an axial bore 30. The intermediate portion of the burner 28 has a peripheral flange 32 adapted to rest upon the upper end of the candle 2. The lower end of the burner 28 is tapered to fit into the upper end of the candle or the fuel tank.

An important feature of the invention resides in the wick 34, which may be made from any suitable material, such for example, as cotton cord which readily absorbs liquid fuel in the tank 8 and conducts it by capillary attraction to the top of the wick where it is ignited.

As shown by Figs. 1 and 4, the wick 34 consists of a central strand 36, and feeder strands 38. The central strand 36 is adapted to extend upward through the axial bore of any of the above-mentioned burners and when lighted provides a flame. As the upper end of the central strand 36 is consumed by the flame the strand is pulled outwardly as needed until its lower end is above the level of the fuel in the tank 8. However, it is supplied with fuel by the feeder strands 38 which remain wholly within the fuel tank 8 where they are not effected by the flame. Preferably, the feeder strands 38 consist of a length of cord formed intermediate its ends into a loop 40, surrounding the upper portion of the central strand 36, which latter may be drawn through the loop from time to time as it is consumed by the flame. By arranging the wick in the manner described

the feeder strands 38 will provide the central strand 36 with a uniform supply of liquid fuel from the tank through capillary attraction. On becoming too short for further use, the central strand 36 may be replaced by another, but the feeder strands 38 may continue in use as they are not affected by the flame.

The fuel tank 8 and wire 14, are used in candles molded from suitable composite material to hold the fuel oil and reinforce the candle, but may be dispensed with when the candle is produced from metal or other strong nonporous material, in which event a fuel chamber is formed within the candle itself.

The candle 2 and the burners therefore may be of a plain or ornamental type. The fuel oil may be so treated as to permeate the surrounding air with a pleasant fragrance while being consumed by the flame. The fuel oil may also be treated to produce flames of different colors, such, for example, as red, white, or green to enhance their appearance.

From the foregoing description taken in connection with the drawing, it is apparent that I have provided a candle possessing the advantages above pointed out, and while I have shown several forms of burners I reserve the right to provide such other forms as properly fall within the scope of the invention as claimed.

Having thus described my invention, what I claim and desire to secure by Letters Patent, is:

In combination, a device comprising a tallow candle having a recess formed in the upper end

thereof, a metallic fuel tank carried in said recess, said fuel tank being closed at the bottom and open at the top, a reinforcing rod rigidly fixed to the bottom of said fuel tank and extending downwardly through said candle, a burner closing the upper end of the candle and provided with an axial bore extending vertically therethrough, and a wick comprising a pair of strands, one of which extends upwardly from the fuel tank and through the axial bore of the burner whereby it is supported, and the other of which is arranged wholly within the fuel tank and formed intermediate its ends into a knot in which the first strand is slidably arranged.

PAUL A. HUNICKE.
